UNITED STATES PATENT OFFICE

150,403

DESIGN FOR A LINK CHAIN FOR A BRACELET OR SIMILAR ARTICLE

Michael Chernow, New York, N. Y.

Application April 5, 1948, Serial No. 145,544

Term of patent 7 years

(Cl. D45—16)

To all whom it may concern:

Be it known that I, Michael Chernow, a citizen of the United States and residing at New York, in the county of New York and State of New York, have invented a new, original, and ornamental Design for a Link Chain for a Bracelet or Similar Article, of which the following is a specification, reference being had to the accompanying drawings, forming part thereof, and in which

Fig. 1 is a plan view of a link chain for a bracelet or similar article, showing my new design,

Fig. 2 is a side elevation thereof, and

Fig. 3 is an enlarged transverse sectional view taken along line 3—3 of Fig. 1.

The dominant feature of my design resides in the element disclosed in full lines, said element being repeated throughout the length of the link chain as indicated by the broken line illustration.

I claim:

The ornamental design for a link chain for a bracelet or similar article substantially as shown and described.

MICHAEL CHERNOW.
